HANDLE FOR CUTLERY OR THE LIKE

Thomas Lamb, New Canaan, Conn.

Application April 7, 1959, Serial No. 55,390

Term of patent 14 years

(Cl. D22—3)

Figure 1 is an elevational view of one side of a handle for cutlery or the like embodying my new design.

The conventional portions of a cutlery blade shown in dotted lines in Figures 1, 2 and 3 are only for the purpose of illustration.

I claim:

The ornamental design for a handle for cutlery or the like, substantially as shown and described.
